(57) **CLAIM**

The ornamental design for an electronic cigarette, as shown
and described.

DESCRIPTION

FIG. 1 is a front view of an electronic cigarette according to a
first embodiment of the present application;

FIG. 2 is a rear view of the electronic cigarette according to
the first embodiment of the present application;

FIG. 3 is a left view of the electronic cigarette according to the
first embodiment of the present application;

FIG. 4 is a right view of the electronic cigarette according to
the first embodiment of the present application;

FIG. 5 is a top view of the electronic cigarette according to the
first embodiment of the present application;

FIG. 6 is a bottom view of the electronic cigarette according
to the first embodiment of the present application;

FIG. 7 is a perspective view of the electronic cigarette accord-
ing to the first embodiment of the present application;

FIG. 8 is a front view of an electronic cigarette according to a
second embodiment of the present application;

FIG. 9 is a rear view of the electronic cigarette according to
the second embodiment of the present application;

FIG. 10 is a left view of the electronic cigarette according to
the second embodiment of the present application;

FIG. 11 is a right view of the electronic cigarette according to
the second embodiment of the present application;

FIG. 12 is a top view of the electronic cigarette according to
the second embodiment of the present application;

FIG. 13 is a bottom view of the electronic cigarette according
to the second embodiment of the present application; and,

FIG. 14 is a perspective view of the electronic cigarette
according to the second embodiment of the present applica-
tion.

The broken lines in the drawings are included for the purpose
of illustrating environmental structure and form no part of the
claimed design.

1 Claim, 14 Drawing Sheets
